UNITED STATES PATENT OFFICE.

ROBERT A. WOOD, OF NEW YORK, N. Y.

RECODER.

No. 876,854.

Specification of Letters Patent.

Patented Jan. 14, 1908.

Application filed June 20, 1906. Serial No. 322,559.

To all whom it may concern:

Be it known that I, ROBERT A. WOOD, a citizen of the United States, and a resident of the city of New York, borough of the Bronx, 5 in the county and State of New York, have invented a new and Improved Recorder, of which the following is a full, clear, and exact description.

The object of the invention is to provide a 10 new and improved recorder, more especially designed for use on rolling mills and other machines, and arranged to accurately record the amount of material fed through the machine by the workmen and the time, thus 15 giving a full and complete record of the operator's work during working hours.

The invention consists of novel features and parts, and combinations of the same, which will be more fully described herein- 20 after and then pointed out in the claims.

A practical embodiment of the invention is represented in the accompanying drawings forming a part of this specification, in which similar characters of reference indicate cor- 25 responding parts in all the views.

Figure 1 is a front elevation of the improvement as applied to a rolling mill, the latter being shown in dotted lines; Fig. 2 is an enlarged front elevation of the improvement; Fig. 3 is a plan view of the same, and Fig. 4 is a side elevation of the improvement as arranged for recording the work done by 30 two machines.

The improved recorder is mounted on a suitable base A, preferably attached to the framework B' of the rolling mill B or other machine on which the recorder is to be used. On the base A is erected a standard A' on which is mounted to rotate the carrier C carrying the indicator card D removably held on one face of the said carrier C by the use of suitable clamps E or the like holding devices. The rolling mill or other machine is driven at a constant or uniform speed, thus 40 allowing the indicator card to be graduated to represent hours. As shown in the drawings the indicator card D is divided into equal sectors D' each representing an hour, so that the face of the indicator card is di- 45 vided, say into ten sectors representing ten working hours of the day. The face of the indicator card D is also divided by concentric circles into annular bands D² representing the working days of the week, as will be 50 55 readily understood by reference to Fig. 2.

The card carrier C is preferably in the

form of a wheel, provided on its peripheral face with a worm wheel C' in mesh with a worm F secured on the upper end of a shaft F' journaled in suitable bearings arranged on the standard A'. On the lower end of the shaft F' is secured a worm wheel F² in mesh with a worm F³ secured on a shaft F⁴ arranged horizontally and journaled in suitable bearings on the base A. On the shaft F⁴ is secured a pulley F⁶ connected by a belt F⁶ with one of the rolls of the rolling mill B; for instance, as shown in Fig. 1, the roll B², between which and the roll B³ passes the material to be treated by the rolling mill. Now, 60 65 70 75 when the rolling mill is driven a rotary motion is transmitted by the gearing described to the carrier C, to give to the latter a complete revolution during the ten hours of a working day, it being understood that the aforesaid gearing is proportioned correspondingly.

On the face of the indicator card D is indicated a stylus G, in the form of a pencil or the like, held in a sleeve G' mounted to slide 80 in a suitable bearing H, having a pin H' mounted to turn in a bearing A³ secured on the base A, to allow of turning the bearing H to bring the stylus G in proper relation to the corresponding week indicated on the face 85 of the indicator card D. When the desired adjustment has been made the bearing H is secured in place by a set screw H² screwing in the bearing A³ against the pin H' (see Fig. 4). The stylus G is normally held out of engagement with the face of the indicator card D and for this purpose a spring G² is employed and coiled on the sleeve G', one end of the spring abutting against the bearing H and the other end resting against a shoulder 90 G³ formed on the outer end of the sleeve G'. An eye G⁴ having a segmental slot extends from the outer end of the sleeve G' and is engaged by the arm I' of a bell crank I fulcrumed at I² on the base A. The other arm 100 I³ of the bell crank lever I is engaged by an arm J secured on a rock shaft J' mounted to turn in a bearing K, preferably attached to the framework B' of the rolling mill. On the rock shaft J' is secured a second arm J² extending into the path of the work passing between the rolls B² and B³ of the rolling mill, the said arm being for this purpose preferably located in the rear of the said rolls B² and B³, as plainly indicated in Fig. 1. Now, 105 110 when the work passes between the rolls B², B³ it engages the arm J² and imparts a swing-

ing motion to the same, so that the shaft J' is rocked and its arm J imparts a swinging motion to the bell crank lever I to push the sleeve G' and its stylus G inward against the 5 tension of the spring G². Now, this inward movement of the stylus brings the point thereof in contact with the face of the indicator card D at a proper hour and day, so that the stylus traces a line on the rotating 10 card D, thus indicating the length of time the work passed through the rolls B² and B³. It is understood that the arm J² is held in the position referred to as long as the work passes between the rolls B² and B³, and as 15 soon as the work ceases to pass between the rolls B² and B³ then the stylus G is released and returned to its normal inactive position by the action of the spring G². Now, when the stylus G returns to its normal inactive 20 position the bell crank lever I and the arms J and J² are returned to their normal position, so that the arm J² is again in position to be engaged by the work next passed through the rolls B² and B³ of the rolling mill.

25 From the foregoing it will be seen that the recorder readily and accurately indicates the time the machine was running idle and also the time the machine was doing work, and hence a full record of the doings of the operator is had.

30 If desired, the indicator cards may be arranged on both sides of the carrier C, and in this case an additional stylus, bell crank lever I and mechanism for operating the 35 same as shown and described is added to the machine, as will be readily understood by reference to Fig. 4. Thus one recorder is used for recording the work done by two machines.

40 The recorder shown and described is very simple and durable in construction, is composed of comparatively few parts and not liable to easily get out of order.

45 Although I have shown a preferred form it is evident that I do not limit myself to the detail construction shown and described, as the same may be varied without deviating from the spirit of my invention.

Having thus described my invention, I 50 claim as new and desire to secure by Letters Patent:

55 1. A recorder for attachment to rolling mills and other machines, comprising a revoluble card carrier driven from the machine and carrying an indicator card, a stylus for the said card and normally held out of contact with the same, and mechanism for moving the said stylus into contact with the said card, and having operating means projecting 60 into the path of the work passing through the machine.

65 2. A recorder for attachment to rolling mills and other machines, comprising a revoluble card carrier driven from the machine and carrying an indicator card, a stylus for

the said card and normally held out of contact with the same by the action of a spring, a bell crank lever engaging the said stylus, and a rock shaft having arms, one engaging the 70 said bell crank lever and the other projecting into the path of the work passing through the machine.

3. A recorder for attachment to rolling mills and other machines, comprising a revoluble card carrier having means for removably supporting an indicator card, a driving mechanism for the said carrier and driven from the machine to which the recorder is applied, a spring pressed slidable stylus for the said card and normally held out of engagement by the action of its spring, a bell 80 crank lever engaging the said stylus, and a rock shaft having arms, one for engagement with the said bell crank lever and the other for engagement by the work passing through 85 the machine.

4. A recorder for attachment to rolling mills and other machines, comprising a revoluble card carrier, means for normally supporting an indicator card on the carrier, 90 a driving mechanism for the said carrier and driven from the machine to which the recorder is applied, a spring pressed slidable stylus for the said card and normally held out of engagement by the action of its spring, 95 an adjustable support for the said stylus, a bell crank lever engaging the said stylus, and a rock shaft having arms, one for engagement with the said bell crank lever and the other for engagement by the work passing 100 through the machine.

5. A record attachment for rolling mills, comprising a revoluble card carrier, means for operating the card carrier from the machine to which the recorder is applied, a 105 stylus for the card, a sliding and spring pressed holder for the stylus, said holder having a slot at its outer end, a bell crank lever having one member engaging the slot of the stylus holder, and a rock shaft, having two 110 arms, one of which extends into the path of the material passing through the mill, and the other engaging the other member of the bell crank lever.

6. In a recorder of the character described, 115 a support, a revoluble card carrier mounted in the support, a vertically adjustable bearing carried by the support, a sliding and spring pressed stylus mounted in the bearing, a bell crank lever having one member engaging the stylus, and means for engaging the other member of the bell crank lever to operate the said lever.

7. In a recorder attachment for rolling 125 mills a support, a revoluble card carrier mounted in the support on a horizontal pivot and having a peripheral worm wheel, a vertical shaft having at its upper end a worm meshing with the worm wheel of the card carrier, and at its lower end a worm wheel, 130

and a horizontal shaft having at one end a worm meshing with the worm wheel of the vertical shaft and at its other end with a pulley.

- 5 8. A recorder for attachment to rolling mills and like machines, comprising a revoluble carrier driven from the machine and carrying an indicator card, a stylus, means for normally holding the stylus out of engagement with the card, means for operating the stylus to hold it in engagement with the card, and means in the path of the material passing through the machine for operating

the stylus operating means, whereby the stylus will be held in engagement with the card so long as the material passes through the machine, and will be disengaged therefrom as soon as the material ceases passing through the machine.

In testimony whereof I have signed my name to this specification in the presence of two subscribing witnesses.
